UNITED STATES PATENT OFFICE.

HARRY L. VAUGHAN, OF CHICAGO, ILLINOIS.

BOTTLE-OPENER.

1,207,100.

Specification of Letters Patent.

Patented Dec. 5, 1916.

Application filed August 21, 1915. Serial No. 46,731.

To all whom it may concern:

Be it known that I, HARRY L. VAUGHAN, a citizen of the United States, residing at Chicago, in the county of Cook and State of Illinois, have invented certain new and useful Improvements in Bottle-Openers, of which the following is a specification.

This invention relates to improvements in bottle openers and has for its object to provide a device of simple and cheap construction for removing crown caps.

Another object of the invention is to provide a combination tool embracing a crown cap remover and cork screw.

15 With the above and other objects in view which will hereinafter be more fully explained, I have invented the device illustrated in the accompanying drawings in which:—

20 Figure 1, is an elevational view of my device shown in operative position, Fig. 2, is a view showing the upper edge thereof, Fig. 3, is a similar view showing the lower edge thereof, Fig. 4, is a plan view of a sheet metal blank from which the device is made, and Fig. 5, is an edge view of a modified form of the device.

Like reference characters indicate like parts throughout the specification and in the 30 several views in the drawings in which—

1 indicates a sheet metal blank stamped in a shape so that when it is bent upon itself on the line A that a fulcrum point 2, a claw 3, and a lever 4 is formed, the latter having 35 an opening 5 at its end 6 for engagement with a key ring. By using a blank which must be doubled upon itself to form the device a perfectly smooth upper edge 7 is provided thus obviating polishing the edge to 40 remove burs. I have found that the greatest difficulty with sheet metal openers is the fact that the lower edge of the lever portion which is engaged by the user's hand in operating the opener cuts the hand and therefore makes the device very unsatisfactory. 45 In order to obviate this nuisance I have provided a cut away portion 8, pressed the corners 9 and 10 apart so as to receive the fixed end 11 of the spiral cork screw 12 which is 50 held pivoted in the recess 13 formed by said

spaced apart corners 9 and 10 by means of a pin or rivet 14. At the opposite end of the cut away portion 8 is an extension 15 having a recess 16 stamped thereon to receive the point 17 of said cork screw 12. The 55 point 17 of the cork-screw is normally out of alinement with the recess 16 so that the cork screw must be sprung in order that the point 17 will enter the recess and therefore the tension of the cork-screw when 60 sprung will hold said point in place in said recess so that in operating the device as a crown cap remover the spiral body of the cork-screw will be engaged by the fingers of the operator and form an enlarged bearing upon which to pull and will consequently not cut the fingers as would the edge 65 of metal.

In Fig. 5 I show a slight modification of the device in which I substitute a screw-driver 18 for the cork-screw the screw-driver blade being pivoted at 19 and the screw engaging end 20 thereof being adapted to seat in a recess 21. The side 22 of the member 18 is formed arcuate to form a bearing for 75 the hand of an operator when the device is being used as a cap remover.

Having now described my invention that which I claim to be new and desire to procure by Letters Patent is:—

80 A bottle cap remover consisting of a metal blank member terminating in a point for engaging the cap of a bottle and an upwardly curved claw, a cork-screw pivoted to said blank member intermediate its ends 85 and having its longitudinal axis at an angle to the longitudinal axis of said blank and a recess formed in the side and near one end of said blank, whereby the free end of said cork-screw is normally out of alinement 90 with said recess, said cork-screw serving as the bearing portion of the handle when in closed position.

95 In testimony whereof I affix my signature in the presence of two witnesses.

HARRY L. VAUGHAN.

Witnesses:

JOHN J. WALSH,
W. J. HUTTON.
